MEANS FOR TREATING HARD SURFACES

Georges Monnet, Chateau de Franiere, Belgium,
assignor to Societe Anonyme des Manufactures des Glaces & Produits Chimiques de Saint-Gobain, Chauny & Cirey, Paris, France

Application May 18, 1935, Serial No. 22,143
In France May 23, 1934

1 Claim. (CL 51—195)

This invention relates to means for treating surfaces of hard bodies, such as marble or articles consisting of vitreous substances, and relates more particularly to means adapted to be applied 5 along with an abrasive to rough or uneven surfaces for the purpose of uniformly grinding or surfacing the same and for increasing the smoothness of surfaces, which were already subjected to a preliminary grinding in order to produce uniformly smoothed or polished surfaces.

An object of the present invention is the provision of simple and inexpensive means through the use of which the surface of a hard article made of marble or a vitreous substance may be 10 quickly and conveniently surfaced.

The above and other objects of the present invention may be realized by covering the surface to be treated by abrasives generally employed for these purposes, and by rubbing said surface with a 20 plurality of hard elements made of metal or the like, each one of which has a comparatively small operative surface exerting a partial surfacing action upon the surface to be treated.

These elements are preferably connected by 25 elastic or resilient means to a common support which presses them against the surface and moves them simultaneously in relation to said surface. The elements are either entirely separated from each other, or are interconnected in 30 such manner that they may assume various angles of inclination in relation to each other.

The operative surface of each element should extend sufficiently far in at least one direction to prevent the element from reaching the bottom of 35 the cavities and the like in the surfaces to be worked, in order to prevent a deepening of these cavities by the action of these elements.

The operative surfaces of the surfacing elements may be either continuous or subdivided by 40 channels or grooves which facilitate the distribution and penetration of the abrasives.

The resilient means connecting each surfacing element with its support may consist of a rubber block, a spring, a pneumatic cushion or the like. 45 The same purpose may be attained by providing a surfacing element which is resilient or elastic, for instance, by forming a surfacing element out of a plurality of resilient metallic blades.

In addition to the above-mentioned resilient 50 means, other suitable means may be used for causing the surfacing elements to move along with their support. It is advisable to employ flexible or easily deformable members which do not hinder those movements of the surfacing elements relatively to the support, which are caused

by the unevenness of the surface to be treated. It is possible to use flexible diaphragms, a system of cords, wires, flexible cables or leaf springs, tapes, cranks, chains or the like.

The invention will appear more clearly from 5 the following detailed description when taken in connection with the accompanying drawings which show, by way of example only, preferred embodiments of surfacing devices as applied to the surfacing of a horizontal surface.

In the drawings:

Figure 1 shows in vertical section and partly in side elevation a circular surfacing device.

Figure 2 is a bottom view of the device shown in Fig. 1.

Figure 3 shows in vertical section a device used for surfacing articles having large dimensions.

Figure 4 shows partly in section and partly in side elevation a device of a somewhat different construction.

Figure 5 illustrates the use of a plurality of leaf springs for the purpose of supporting the surfacing members.

Figure 6 illustrates the use of a flexible diaphragm for the same purpose.

Figure 7 shows partly in section and partly in side elevation a device, the surfacing elements of which consist of interconnected metallic blocks.

Figure 8 illustrates a different method of interconnecting the metallic blocks.

Figure 9 shows in vertical cross section along the line 9—9 of Figure 11 a device wherein the surfacing elements consist of a plurality of inclined blades.

Figure 10 is a side elevation of the device shown in Fig. 9.

Figure 11 is a bottom view of the device shown in Figs. 9 and 10.

Figure 12 is a section along the line 12—12 of Fig. 9 on a larger scale.

Figure 13 is similar to Fig. 9 and shows one of the surfacing blades on a larger scale.

Figure 14 illustrates a blade of a somewhat different construction.

Figure 15 is a vertical section through surfacing means of a different type.

The device illustrated in Figs. 1 and 2 of the drawings is a circular surfacing device. This device comprises a rigid disc or support 20 which is mounted upon a vertical shaft 21, and is rotatable 50 along with this shaft. The shaft 21 is driven by means of a belt 22, passing around a pulley 23, which is keyed upon the shaft 21.

Any suitable means not shown in the drawings, may be used for moving the shaft 21 and the disc 55

20 in the vertical direction, i. e. in the direction of the longitudinal axis of the shaft 21. By this movement, the surfacing elements 36 are brought in contact with the surface to be treated. The 5 pressure which is exerted by the surfacing elements 36 upon the surface to be treated is caused partly by the weight of the disc 20 and partly by a weight 24, adjustably mounted upon a lever 25, which transmits the pressure of the weight 24 to the shaft 21. The lever 25 is pivoted at 26 to a fixed support 27 which comprises a sleeve 28 surrounding the shaft 21 provided with ball bearings allowing the shaft 21 to rotate and slide therein.

15 The device is provided with a plurality of rubber buffers 29, the upper edges of which are glued or otherwise firmly attached to metallic plates 30 which are connected by bolts 31 to the support 20.

20 The lower edges of the resilient buffers 29 are glued or otherwise firmly attached to metallic plates 32, which are connected by bolts 33 to metallic surfacing elements 36. As shown in Figure 1, the surfacing elements 36 may be conveniently removed and replaced by new ones when worn out.

25 A flexible or deformable diaphragm 34 may be interposed between the elements 36 and the plates 32. The edges of the diaphragm 34 are attached by bolts 35 to the support 20, so that the buffers 29 are protected from dirt and dust.

The arrangement of the surfacing elements 36 upon the disc 20 is illustrated in Figure 2 of the drawings. Grooves 37 are formed between the 35 blocks 36 and serve the purpose of distributing more uniformly the abrasives applied to the treated surface during surfacing.

The surfacing device illustrated in Figure 3 of the drawings is used for treating articles having 40 large dimensions. Obviously, the device must be correspondingly large and must be adapted to transmit a substantial pressure upon the surface to be treated. The device comprises the support 40 and a plurality of rubber supports 41 connected to upper plates 42, which are attached by bolts 43 to the support 40. Surfacing blocks 49 are provided with grooves 44 and are attached by bolts 45 to the lower plates 46 which are firmly connected with the lower edges of the rubber supports 41. A flexible diaphragm 47 is interposed between the blocks 49 and the plates 46 and is attached by bolts or the like to rigid supports 48, which are firmly connected to the undersurface of the support 40. Due to the provision of the 50 diaphragm 47 a movement of the surfacing blocks 49 in the horizontal direction is assured although these blocks remain free to move relatively to each other in the vertical direction.

In some instances rubber supports 41 were 55 found to be insufficient for the transmission of large pressures. In the modification shown in Figure 4 the rubber supports are substituted by coiled springs 58 which surround rods 51, passing through suitable openings formed in the support 52.

The flexible diaphragm 54 is clamped between suitable flanges formed upon the surfacing elements 55 and the washers or flanges 53 of the rods 51, and is carried by supports 56 attached to the 70 support 52. Figure 4 shows that the rods 51 support the surfacing elements 55 over the surface to be treated and that these elements are independently movable in relation to each other during the surfacing process.

75 In the device shown in Figure 5 of the draw-

ings, the surfacing elements 60 are connected with the supporting plate 61 by a plurality of leaf spring arrangements 62, which are of the same type as those employed in carriages and the like. The leaf springs 62 are attached by brackets 63 to the plate 61 and are connected by links 64 to supports 65 which are firmly attached by suitable bolts 66 to the surfacing elements 60. A flexible diaphragm 67 is interposed between the supports 65 and the surfacing elements 60. The leaf springs 62 cause a horizontal movement of the elements 60 and permit a relative vertical adjustment of these elements.

In the modification shown in Figure 6, the surfacing elements 70 are firmly attached to the undersurface of a flexible bag-shaped diaphragm 71, the upper surface of which is attached to the support 73. A vertical shaft 74 which is supported by a sleeve 75 is firmly connected with the support 73 so that the support is rotatable and movable in a vertical direction along with the shaft 74. The support 73 carries a valve 76 which communicates with the interior of the bag-shaped diaphragm 71 and which is adapted to transmit a fluid under pressure, for instance compressed air, into the interior of the bag-shaped diaphragm 71.

The diaphragm 71 is preferably made similar to pneumatic cushions and consists of an outer cover of a durable material which surrounds an inner bag made of flexible and air-tight rubber.

The devices shown in Figures 7 and 8 are used in connection with surfacing elements consisting of comparatively large metallic blocks. The object of these constructions is to connect these blocks with each other in such manner that they may be inclined relatively to each other, but that for the adjacent parts of two adjacent elements their vertical displacements are not independent. These devices are particularly useful when the 40 surfacing device extends out of the surface of the plates to be worked and when the level of a surfacing element may be such that the element could strike against the edges of the plates.

In the modification shown in Figure 7, two 45 blocks 80 are connected with each other by a hinge 81 which is attached to a plate 82 firmly connected with the lower edges of an elastic support 83. A plate 84 connects the support 83 with the support 85. Due to this arrangement, the 50 edges 86 of two contiguous elements 80 are always maintained at the same distance from the support 85.

Obviously, a resilient blade or any other suitable means may be used instead of the hinge 81.

In the modification shown in Figure 8, the surfacing elements 90 are attached by bolts 91 to plates 92 or 98, respectively, firmly connected with the lower edges of resilient supports 93. The plates 94 connect the supports 93 to the rotatable 60 support 95.

The plate 92 is provided with a projection 96, one end of which is situated within a groove 97 formed in the plate 98.

Due to this arrangement the plate 98 may be 65 inclined in relation to the plate 92. At the same time the projection 96 prevents the plate 92 or the edge of the plate 98 from being moved much lower or much higher than the adjacent edge of the other plate.

The device illustrated in Figures 9 to 13 of the drawings, comprises a rotatable support 100 which is firmly mounted upon a vertical shaft 101. The support 100 carries the surfacing elements consisting of inclined metallic blades 102 which form 75

acute angles with the under surface of the support 100 and with the surface 109 of the article to be treated (Fig. 10). Bolts 103 passing through dove-tailed wedges 108 (Fig. 13) may 5 be used for attaching the blades 102 to the plate 100. Obviously, the blades 102 may be glued or welded to the support 100, or attached thereto by any other suitable means.

10 Spacing members 104 are arranged close to the under surface of the plate 100 and are used for the purpose of maintaining the blades 102 at a predetermined distance from each other. Due to this arrangement abrasives can easily penetrate into the spaces provided between the blades and 15 will uniformly cover the entire surface to be ground or polished.

10 In some instances it may be advisable to mount the blades upon separate blocks which are then attached to the block 100. The blades 102 may 20 have any suitable thickness and length.

25 In the modification shown in Figure 14 each blade 102 of Fig. 13 is subdivided into three blade members 110 which are separated from each other by slots 111 and which are all connected to a common member 112 which is attached by bolts 113 and dove-tailed wedges 115 to the rotatable support 114.

30 The effect attained by the above-described devices is also obtainable merely by covering the operative surface of a surfacing block 120 (Fig. 15) by a mixture comprising hard granules 121 and granules or particles 122 of a less hard and elastic substance, such as rubber, cork or the like. Any suitable binding material 123 may be 35 used for interconnecting the particles of these two substances.

40 After this layer has been applied to the surface to be treated for some time, it will be found that the particles 122 and the binding substance 123 surrounding the hard granules 121 will be destroyed or worn away more quickly than these 45 granules, so that grooves or channels will be formed upon the surface of the layer, which are suitable for the purpose of spreading an abrasive over the entire surface to be treated.

45 The rigid surfacing elements of the described devices function in substantially the same manner as the hard granules 121 while the elastic particles 122 and the binding substance 123 form an elastic connection between the separate granules 121 and also between these granules as a whole and the means for moving them relatively to the surface to be treated.

50 All of the above described devices operate in substantially the same manner. Any one of them is placed over the surface 109 to be treated (Fig. 10), which is covered by abrasives 108 of the

standard type. Then the support carrying the surfacing elements is rotated and is moved downwardly toward the surface 109, bringing the surfacing elements in contact with this surface. In operation, the surfacing elements exert a certain 5 predetermined pressure upon the surface to be treated, while they are moved over this surface.

10 One of the characteristic features of all these devices is the fact that the rigid surfacing elements are capable of relative movement in relation to each other, for instance, they may form various angles of inclination one with the other. At the same time, suitable means may be provided for preventing any vertical displacement 15 between the adjacent edges of two adjacent surfacing elements.

20 Due to the rigidity of each surfacing element and to its elongated form, the element cannot reach to the bottom of the cavities or grooves located upon the surface to be treated so that 25 such grooves cannot be deepened by the surfacing elements. This is an important advantage of the surfacing devices constructed in accordance with the principles of the present invention, as compared to felts.

25 Since the operative surface of each of the surfacing elements is comparatively small and since each surfacing element is elastically and resiliently connected with its support, all the surfacing elements remain continuously in contact with 30 the surface to be treated and follow this surface even if it is extremely uneven.

35 Due to the fact that the surfacing elements are totally or partly separated from each other, and are connected by resilient means with their support, each of the surfacing elements may 40 exert a predetermined pressure upon the surface with which it is in contact. This pressure may be either a constant one or it may vary depending upon the value of the projections to be leveled.

45 What is claimed is:

50 Means for treating glass surfaces, comprising a rotatable support, a vertical axle carrying said support, and a plurality of spaced resilient blades inclined at an acute angle to the plane of the surface to be treated, each of said blades being connected to the lower portion of said support, and spacing members maintaining each blade apart from the other blades, each of said blades having a rigid, thin and elongated surface which is substantially parallel to the surface to be treated, the longitudinal direction of said blades being at an acute angle to the direction of the movement of the support. 55

GEORGES MONNET.
